APPARATUS FOR EXTINGUISHING OIL AND GAS WELL FIRES

Filed Aug. 26, 1929

A diagram of a knot, specifically a double loop knot, shown in a perspective view. The knot has three distinct segments labeled with numbers: '18' is on the leftmost segment, '20' is on the top segment, and '24' is on the rightmost segment.

APPARATUS FOR EXTINGUISHING OIL AND
GAS WELL FIRES

Joseph P. Collins, Bakersfield, Calif.

Application August 26, 1929. Serial No. 388,540

5 Claims. (Cl. 169—4)

My invention relates to and has for its purpose the provision of an apparatus by which oil, gas or other fluid issuing from a well, can be controlled in a manner to extinguish a burning oil or gas well; or in the case of a gusher, to enable workmen to approach the gusher without being subjected to a shower of oil from the ascending oil column.

I will describe only one form of apparatus for extinguishing oil and gas well fires and will then point out the novel features thereof in claims.

In the accompanying drawing,

Figure 1 is a view showing in plan one form of apparatus embodying my invention.

Figure 2 is a vertical sectional view taken on the line 2—2 of Figure 1, and illustrating one position of the apparatus with respect to a burning well.

Figure 3 is a view similar to figure 2 and illustrating another position of the apparatus with respect to the well, and

Figure 4 is a detail sectional view taken on the line 4—4 of Figure 2 and looking in the direction of the arrows.

Referring specifically to the drawing in which similar reference characters designate similar parts in each of the several views, my invention in its present embodiment comprises a carriage C constructed of a pair of spaced apart and parallel longitudinal members 10 and 11 and a pair of spaced apart and parallel transverse members 12 and 13 secured in intersecting relation to the longitudinal members by bolts 14 or other fastening members. The longitudinal and transverse members are in the form of metal beams preferably of discarded railroad rails for the sake of cheapness and to render the carriage of great weight so as to prevent its being lifted off of the ground under the force of a column of burning fluid issuing from a well.

One end of each longitudinal member 10 and 11, is curved upwardly as indicated at 15 and is connected to one end of a suitable hauling cable 16 adapted to be connected at its other end to a motor truck, tractor, or other hauling apparatus, for pulling of the carriage thereby over the ground. Other cables 17 are connected to the members 10 and 11 for pulling the frame laterally to aid in placing the frame in the desired position with respect to a well.

Intermediate the longitudinal and transverse members 12 and 13, is supported in an upright position on the carriage, an open ended conduit 18, the lower open end of which constitutes an inlet and the upper end an outlet for a column of

burning fluid issuing from a well. The conduit which is preferably constructed of heavy gauge metal pipe is of somewhat larger than the diameter of the bore hole from which the column of burning fluid is issuing, and the conduit is supported from the carriage with its lower end substantially at the ground level or in contact with the ground, by means of straps 19 secured to the conduit and to the transverse members of the carriage by suitable fastening members. The conduit is supported in its upright position by guy wires 19^a connected at intervals to the conduit and to the carriage. The conduit 18 broadly constitutes a means operable when brought to a position directly over the bore hole of a burning well, to confine the column of burning fluid to a predetermined height above the ground level.

Directly to the rear of the conduit 18, a second and open ended conduit 20, also formed of heavy gauge metal pipe of the same diameter as the conduit 18, is supported on the carriage by other straps 21 connected to the transverse members, with the lower open end of the conduit 20 constituting an inlet and being disposed at substantially the same level as that of the lower open end 80 of the conduit 18 and in such close proximity thereto as to virtually form a continuation of the lower open end of the conduit 18 to the rear side of the latter.

The conduit 20 preferably curves upwardly and rearwardly of the carriage C, so that its upper open end which constitutes an outlet, is directed away from the conduit 18 and is disposed at a considerable distance rearwardly of the latter. The conduit 20 is also supported by guy wires 22 connected thereto and to the conduit 18, and other guy wires 23 connected to the carriage. The conduit 20 broadly constitutes a means for directing and conducting fluid issuing from a well, away from the conduit 18 for a considerable distance before the fluid discharges from the conduit 20 into the atmosphere in a substantially horizontal direction or a direction other than vertical, and at a height preferably less than the height of the conduit 18.

It will be noted that the confronting sides of the conduits 18 and 20 at the lower ends thereof, are flattened as indicated at 24 in Figure 4 so as to prevent escape of fluid around the conduits between the two when the apparatus is moved with respect to the well from the position shown in Figure 2 to that shown in Figure 3.

In the operation of the apparatus, the carriage C is first drawn over the ground by a suitable hauling apparatus attached to the cable 17, to-

wards the burning well to the position shown in Figure 2 wherein the conduit 18 is in registration with the bore hole of the well so that the column of burning fluid issuing from the well 5 will traverse the conduit and be free to issue from its open upper end.

As the conduit 18 confines a portion of the burning fluid column to a predetermined height above the ground, and excludes the air necessary 10 to support combustion therein, the confined portion of the burning fluid column extinguishes. That portion of the fluid column above the upper end of the conduit 18 continues to burn as it is constantly being fed by unburned fluid ejected 15 from the upper end of the conduit.

Should there be any burning debris or other material on the ground in the vicinity of the well, this is now extinguished by water, chemicals or other suitable means, after which the carriage is 20 quickly moved forwardly by the hauling apparatus from the position shown in Figure 2 to that shown in Figure 3 wherein the conduit 18 is moved out of registration with the bore hole, and the lower open end of the conduit 20 into registration with the bore hole, thus separating or cutting off from the conduit 18, the supply of unburned fluid issuing from the bore hole, and permitting the unburned fluid to discharge into the open lower end of the conduit 20. The unburned 30 fluid issuing from the bore hole is now directed and conducted by the conduit 20, laterally away from the conduit 18 a sufficient distance before discharging from the conduit 20, to prevent its ignition by the burning column of fluid above 35 the conduit 18. As the burning column of fluid above the conduit 18 is no longer being fed with unburned fluid from the well, it quickly burns out, and the fire is thereby completely extinguished.

It is to be understood that in the event any 40 appreciable wind is blowing during the extinguishing operation, the forward direction of movement of the carriage C will preferably be directly opposite to the direction of the wind, so as to insure that the force of the wind will not 45 blow any of the unburned fluid when discharging from the conduit 20, in sufficiently close proximity to the burning column of oil above the conduit 18, to cause its ignition.

From the foregoing description, it will be mani- 50 fest that by my apparatus, a burning well can be extinguished with the utmost ease and dispatch, and that by moving the conduits 18 and 20 laterally across the column of fluid issuing from a well so that only the end edges of the conduits are presented to the upwardly moving fluid 55 column, that the tendency of the latter to raise or overturn the apparatus will be overcome, as the movement of the fluid column at its high velocity and pressure is practically unobstructed 60 by the conduits.

In the event of a gusher in which oil is issuing 65 from a well under gas pressure or in extinguishing a fire at a well from which only burning gas is issuing, the upright conduit 18 can be dispensed with and only the conduit 20 provided on the carriage C.

With the use of only the conduit 20 at a gusher, 70 the carriage C will be moved over the ground to register the lower open end of the conduit with the hole, so that the oil will be forced by the gas through the conduit and directed upwardly and laterally of the hole before being discharged from the conduit, thus conveying the oil away from the hole and enabling workmen to conveniently 75 approach the hole without being subjected to a

shower of oil which would otherwise fall around the hole from the ascending oil column.

In using the conduit 20 to extinguish a burning gas well, the carriage C is moved over the ground until the lower open end of the conduit registers with the hole, thus causing the column of burning gas to be directed upwardly and laterally of the hole through the conduit and the burning gas thereby caused to be extinguished in the conduit, and the gas to burn only beyond the laterally directed outlet at the upper end of the conduit. Should there be any burning debris around the hole, this is now extinguished by water or other suitable means, after which the carriage is shifted to move the lower end of the conduit 20 clear of the hole so as to permit the unburning gas now issuing from the hole, to ascend vertically. As the supply of gas from the hole through the conduit to the gas burning beyond the outlet of the conduit, is now cut off, the gas issuing from the conduit will burn itself out, and the fire will thus be entirely extinguished.

Although I have herein shown and described only one form of apparatus for extinguishing oil and gas well fires embodying my invention, it is 100 to be understood that various changes and modifications may be made therein without departing from the spirit of the invention and the spirit and scope of the appended claims.

I claim:

1. An apparatus of the character described comprising a carriage movable over the ground, means supported by the carriage for confining a column of burning fluid issuing from a well, to a predetermined elevation above the ground 110 level to cause the confined portion of the fluid column to extinguish and the fluid column to burn only above its confined portion, when the carriage is moved to one position with respect to the well hole, and means supported by the 115 carriage for directing the unburning portion of the fluid column as issuing from the mouth of the well, away from the burning portion when the carriage is moved to a second position with respect to the well hole, so as to cease feeding 120 the burning portion with unburned fluid, and thereby cause the burning portion of the fluid column to extinguish.

2. An apparatus of the character described comprising a carriage movable over the ground, 125 an upright open ended conduit supported by the carriage, for positioning to receive and confine to a predetermined height above the ground, a column of burning fluid issuing from the mouth of a well, and a second conduit supported by 130 the carriage, having its upper end open and directed away from the upright conduit at one side of the latter, and its lower end open and in close proximity to the lower end of the upright conduit, for positioning to receive and direct fluid issuing from the mouth of the well 135 in a direction laterally away from the upright conduit.

3. An apparatus of the character described comprising a carriage movable over the ground, 140 an upright open ended conduit supported by the carriage, for positioning to receive and confine to a predetermined height above the ground, a column of burning fluid issuing from the mouth of a well, and a second conduit supported by the 145 carriage, having its upper end open and directed away from the upright conduit at one side of the latter, and its lower end open and forming a continuation of the upright conduit at one side of the latter for positioning to receive and 150

direct fluid issuing from the mouth of the well in a direction laterally away from the upright conduit.

its open lower end in close proximity to the lower open end of the upright.

4. An apparatus of the character described comprising a carriage movable over the ground, an upright open ended conduit supported by the carriage, for positioning to receive and confine to a predetermined height above the ground, a column of burning fluid issuing from the mouth of a well, and a second open ended conduit supported by the carriage and curving outwardly from the upright conduit, with its upper open end directed away from the upright conduit, and

5. An apparatus of the character described comprising a carriage movable over the ground, a conduit supported by the carriage in an upright position and having a downwardly opening inlet at its lower end and an upwardly opening outlet at its upper end, and a second conduit supported by the carriage, and having a downwardly opening inlet at its lower end in close proximity to the inlet of the first conduit, and an outlet at its upper end opening in a direction away from the first conduit.
